EX

OR D 12,628

DESIGN FOR A STOVE.

Design No. 12,628, dated December 27, 1881.

UNITED STATES PATENT OFFICE.

H. CLAY BASCOM AND CYRUS A. HODGES, OF TROY, AND TOBIAS S. HEISTER,
OF LANSINGBURG, NEW YORK, ASSIGNEES TO N. S. VEDDER PATTERN
WORKS, BASCOM, GALBRAITH & CO., OF TROY, NEW YORK.

DESIGN FOR A STOVE.

SPECIFICATION forming part of Design No. 12,628, dated December 27, 1881.

Application filed November 25, 1881. Term of patent 7 years.

To all whom it may concern:

Be it known that we, H. CLAY BASCOM and CYRUS A. HODGES, each a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for 10 Cooking-Stoves, of which the following is a specification, reference being had to the accompanying cut, print, or engraving of a stove having said new design.

The design for the balustrade A is not a part 15 of this invention.

The design for the pipe B consists of the upper compound ornament, *a*, in combination with the lower columnar arched-top ornament, *b*, and angular corner ornaments, *c*, each shaped 20 and all arranged together substantially as shown in the accompanying print.

The design for the panel ornament C consists of the representation of a sailing-vessel, *d*, on water, *e*, surrounded by the ornamented 25 scroll-arch border *f*, having an ornamented base, *f'*, all shaped and arranged together so as to appear substantially as represented in the accompanying engraving.

The design for the outer portion of the panel 30 D consists of the lower triangular corner ornaments, *g g*, having vinelet-scrolls, in combination with the upper vine ornaments, *h h'*, all shaped and arranged substantially as shown in the aforesaid cut.

The design for the oven-door consists of the panel ornament C, composed of the parts *d e f f'*, as above specified, in combination with the panel D, having the ornaments *g g h h'*, as above described, and all disposed so as to present 35 substantially the same appearance as is represented in the aforesaid print.

The design for the panels E F consists of the central ornament, *i*, representing a sloop-like vessel sailing on water under an ornamented 45 scroll-arch, in combination with the lower corner ornaments, *j*, and vine ornament *k*, all shaped and arranged together substantially as shown in the aforesaid cut.

The design for the closet-door G consists of 50 the central panel ornament, *l*, composed as shown, in combination with the lateral corner ornaments, *m m'*, and lateral vine ornaments

n n', all shaped and arranged together so as to produce the appearance represented in the aforesaid engraving.

The design for the side and end plates, H, of the stove-support consists of the central ornamented arch, *o*, over the ornament *p*, with the right and left extending vine ornaments *q q'* and lower ornamental border, *r*, all shaped 60 and arranged substantially as represented in the aforesaid print.

The design for the corners of the stove-support consists of the upper ornamented panel, *s*, and the compound leg ornament *t*, all shaped 65 and arranged substantially as shown in the aforesaid cut.

What we claim as our joint invention is—

1. The design for the pipe B, consisting of the compound ornaments *a b c*, all shaped and 70 arranged as set forth.

2. The design for the panel ornament C, composed of the parts *d e f f'*, all shaped and arranged together as set forth.

3. The design for the outer portion of the 75 panel D, consisting of the ornaments *g g h h'*, all shaped and arranged as set forth.

4. The design for the oven-door, consisting of the ornament C, composed as specified, in combination with the panel D, ornamented as described. 80

5. The design for the panels E F, each composed of the ornaments *i j k*, all shaped and arranged together as set forth.

6. The design for the closet-door G, composed of the ornaments *l m m' n n'*, all shaped 85 and arranged as set forth.

7. The design for the side and end plates, H, of the stove-supporting base, consisting of the parts *o p q q' r*, all shaped and arranged as set 90 forth.

8. The design for the corners of the stove-support, consisting of the parts *s t*, composed and arranged as shown and described.

In testimony whereof we hereunto set our 95 bands, in the presence of two subscribing witnesses, this 22d day of November, 1881.

H. CLAY BASCOM.
CYRUS A. HODGES.
TOBIAS S. HEISTER.
